UNITED STATES PATENT OFFICE.

INDALECIO NORIEGA, OF MEXICO, MEXICO.

TWIN PHONOGRAPH.

1,358,171.

Specification of Letters Patent.

Patented Nov. 9, 1920.

Application filed July 24, 1919. Serial No. 313,072.

To all whom it may concern:

Be it known that I, INDALECIO NORIEGA, subject of the King of Spain, residing at Mexico city, Federal District, Mexico, have 5 invented certain new and useful Improvements in Twin Phonographs, of which the following is a specification.

This invention relates to a double phonograph for recording and reproducing musical works and the like continuously regardless of their length or duration, and to a commutator board by means of which the operation of the phonograph may be controlled at will; and its main object is to 10 15 provide a means for recording musical works of any length on a series of successive disks.

Another object of the invention is to provide electrical connections between the phonograph and the commutator board from 20 which either of the disk carriers or turntables can be brought into operation automatically and as desired.

The invention also comprises electrical 25 means in the phonograph for stopping the motor, and other means for instantaneously changing the action of the motor from either one to the other of the disk carriers.

I obtain these results by means of the 30 construction shown in the accompanying drawings in which:

Figure 1 is a front elevation, partly in section of the double phonograph;

Fig. 2 is a plan of the same;

Fig. 3 is an elevation of the double phonograph showing the forked tone arm;

Fig. 4 is a front elevation of the disk carrier shaft and its supports;

Fig. 5 is a side elevation of the same.

Fig. 6 is a vertical transverse section of 40 the forked horn showing the changeable damper;

Fig. 7 is a plan of an engraved disk;

Fig. 8 is a diagram of the commutator 45 board showing its connections to the phonograph.

Referring to the figures: (1) is the bottom of the case or box on which is mounted motor (2), provided with a hollow feathered 50 shaft (3) extending through the motor. On shaft (3) slide clutches (4) meshing with worm gears (5), which revolve in bearings (7) and which transmit motion selectively to either of the two vertical shafts (6^a) or (6^b) of the disk carriers or turntables. Said 55 clutches are connected to the cores of sole-

noids (8^a) and (8^b) by means of suitable rods mounted to slidably revolve in the worm gears (5), and are further supported in bearings (9^a) and (9^b). Guides (10) are 60 flexibly mounted on these bearings (9^a) and (9^b) and project into channels (11) on the clutches, so as to keep the latter from slipping longitudinally along shaft (3).

Standards (12) are disposed opposite to 65 worm gears (5) and carry shafts (6^a) and (6^b), which are provided with cog-wheels (13^a) and (13^b) to be operated by said worm gears (5). These shafts are provided at their upper extremities with cones (14), 70 on which are mounted the disk carriers (15) provided with ribs (16), the hubs (17) of said disk carriers fitting over said cones (14) and resting on collars (18) of shafts (6^a) and (6^b). Disk carriers (15) are pierced by contact projections (19^a) and (19), which toward their lower extremities terminate in 75 contact brushes (20^a) and (20), which sweep annular metal plates (21^a) and (21^b), which are electrically connected with binding posts 80 (22^a) and (22^b) on the under side of top (23) of the case of the phonograph. This cover (23) is longitudinally divided into two sections so as to facilitate the taking 85 down of the apparatus, and each of these sections has a spring contact (92) and (90) to allow for the rapid connection of the wires of the electric circuit.

On cover (23) of the case is mounted a 90 tubular support (25) for carrying the bifurcated tone arm (26), whose two branches are joined by a union (27), which carries the horn (not shown) and in the interior of which is made to oscillate a damper (28), which may be moved from one opening to 95 the other. Said damper has rigidly connected to its lower-portion an arm (29) which is fixed to a small stud or axle (30) pivotally mounted within the union (see Fig. 6). To this stud (30) there is fixed a 100 depending arm (31) which has a pin-and-slot connection with the adjacent end of a small lever (32) which is pivoted at (33) within the union (27). This lever (32) is operated by a wire (34), whose lower end is 105 eccentrically pivoted to disk (36) at point (35), said disk (36) revolving on a central axle fixed on the interior of the case of the phonograph, as may be seen in Fig. 1. Another wire (37), also eccentrically fixed to 110 disk (36), connects it with reversing lever (39). Lever (39) is provided with adjust-

ment perforations at one end and, at the other, with a notch (40) which engages flange (41) of the core of the solenoid (8^b), which latter can, therefore, transmit movement to the damper and cause it to cut out either branch of the tone arm according as either side (a) or (b) is being operated. Branches (26) of tone arm terminate in reproducing or recording diaphragms (42^a) and (42^b), with needles (43).

10 The complete records, as shown in Fig. 7, are provided with a guiding slot (44), to guide needle (43) directly to the grooves on the record where the phonographic reproduction commences.

15 Motor (2), of the phonograph, is directly connected to source of current (A), on the commutator board, the current passing through post (50), to (51), thence to post (52) in the phonograph case, to (53) and (54), entering the motor at (55). Interruptible current, from the other pole (B) is taken from post (56) on the commutator board thence through (57) and (58) to switch (59), through (60) to post (61) on the phonograph case, through the usual starting and stopping push button contacts (62) and (63), to (64) and (65), entering the motor at (66) and establishing the circuit.

20 Current for energizing solenoid coil (8^a) is taken from line (A) at post (54) in the phonograph case and enters the coil at (76), while the indirect connection is made to line (B) at (65), whence it passes through wire (65') and contact (71) to the base plate (72) of the tubular support (25), Fig. 3, from where it is taken by wire (73) to the metal portion of reproducer (42^a) as indicated in Fig. 3; it then passes through brush (45) to contact (19) and metal brush (20), then through plate (21^b), post (22^b), and wire (90') to contact (90) and thence by wire (90') to post (74) and enters the coil at (75).

25 Current for energizing solenoid coil (8^b) is taken through direct connections from line (A) at (53) and enters the coil at (81). The indirect connection to line (B) is made from plate (72), through wire (77) to reproducer (42^b); then to brush (45^b), post (19^a), brush (20^a), plate (21^a), post (22^a) and wire (92') to contact (92) and thence through wire (92') to contact (78) and enters the coil at (80), completing the circuit.

30 In order to cause either side (a) or (b) to be operated from the commutator board while motor (2) is inactive, the following installation will be used: the motor being already directly connected to (A) connection will be taken from line (B), should it be desired to energize coil (8^a), at post (56), through (57) and (82) to push button contact (83) and post (84), all on the board, and to post (85) on the case of the phonograph, thence to (74) and into the coil at

(75), closing the circuit. To energize coil (8^b), already directly connected to pole (A), connection is made with (B) at (56), through (57) and (82) to push button contact (86) and post (87), all on the board, 70 and thence to post (88) on the case of the phonograph, through (78) and into the coil at (80), thus completing the circuit.

In order to energize either of coils (a) or (b) from the phonograph itself, push button 75 contact (89), which receives current from plate (72), is operated and current passes to spring contact (90), then through wire (90') to post (74) and into coil (8^a) at (75).

To energize coil (8^b), push button contact 80 (91) is operated and current passes from plate (72) through spring contact (92) and wire (92') to post (78) and into coil (8^b) at (80).

From the foregoing description of the 85 electrical connections it will be readily understood that when the needle of the reproducer or the recorder, as the case may be, has traveled over the grooved zone of the record on side (b) of the phonograph the brush (45) 90 establishes contact with the brush (20), and the clutch of the opposite side is automatically brought into mesh and the second disk begins to revolve, thus continuing the reproduction on the second disk; when the latter has run its course, contact is established through the brushes (45^a) and (20^a), and the first side begins to revolve again, and so on continuously, there being ample time for the concluded disk to be replaced by a new one, 100 either for recording or reproducing, regardless of the duration of the composition.

Having thus fully described my invention what I claim is:

1. In a twin phonograph, the combination 105 of a pair of record supports; a single motor; driving connections between the motor and each support, each driving connection including a clutch; a tone arm individually coöperative with each carrier; automatic mechanism for simultaneously opening one clutch and closing the other when either tone arm reaches the end of its travel over a record on the associated support; and mechanism operable automatically simultaneously with the operation of both clutches 110 for blocking the delivery end of the tone arm which has completed its travel.

2. In a twin phonograph, the combination 115 of a pair of record supports; a single motor; driving connections between the motor and each support, each driving connection including a clutch; a tone arm individually coöperative with each carrier; automatic mechanism for simultaneously opening one clutch and closing the other when either tone arm reaches the end of its travel over a record on the associated support; damper mechanism common to both tone arms for blocking the delivery ends thereof in alter- 120

125

130

nation; and mechanism operable automatically simultaneously with the clutch-operating mechanism for actuating the damper mechanism.

5. 3. In a twin phonograph, the combination of a pair of record supports; a motor for driving them; electro-magnetically operated clutches for controlling the motor drive; a tone arm individually cooperative with each support; mechanism for automatically opening either clutch and simultaneously closing the other, whereby the motor is enabled to drive said supports in alternation; damper mechanism associated with said tone arms to open or close their delivery ends to the passage of sound waves therethrough; and a mechanical device connected immediately to the magnet of one of said clutches for actuating the damper mechanism.
6. 4. In a twin phonograph, the combination of a pair of record supports; mechanism for driving them in alternation; a tone arm individually cooperative with each support; a damper common to both tone arms for blocking the delivery ends thereof; a flexible operating element connected to the damper; and connecting means between the driving mechanism and the damper operating element for automatically exerting a pull upon the latter to actuate the same each time the drive is shifted from one support to the other.

7. In a twin phonograph, the combination of a pair of record supports; mechanism for driving them in alternation; a tone arm individually cooperative with each support; a damper common to both tone arms for blocking the delivery ends thereof; a flexible operating element connected to the damper; a pivotally mounted disk to which said flexible operating element is eccentrically connected; and a flexible connection between said disk and said driving mechanism for automatically turning the disk each time the drive is shifted from one support to the other, to actuate said flexible operating element and said damper.

8. In a twin phonograph, the combination of a pair of record supports; a motor for driving them; a tone arm individually cooperative with each support; a pair of alternately-acting electro-magnetic devices for periodically shifting the drive from one support to the other, said devices having their activity reversely changed simultaneously; a damper common to both tone arms for blocking the delivery ends thereof in alternation; and a mechanical connection between one of said electro-magnetic devices and said damper for automatically actuating the latter each time the drive is shifted.

7. In a twin phonograph, the combination of a pair of record supports; a motor for driving them; a tone arm individually cooperative with each support; a pair of alternately-acting electro-magnetic devices for periodically shifting the drive from one support to the other; a damper common to both tone arms for blocking the delivery ends thereof in alternation; a rocking element directly connected to one of said electro-magnetic devices to be operated thereby each time the drive is shifted; and a flexible operating connection between said rocking element and said damper. 65

8. In a twin phonograph, the combination of a pair of record supports; a motor; an electrical system for driving said supports in alternation from the motor and including a circuit for the motor; a controller board to which the terminals of the motor circuit are connected; and devices carried by said board for effecting an initial selective drive of either support. 80

9. In a twin phonograph, the combination of a pair of record supports; a motor; an electrical system for driving said supports in alternation from the motor and including a circuit for the motor and a pair of electro-magnetic devices for determining the support to be driven; a controller board to which the terminals of the motor circuit are connected; and means carried by said board for selectively energizing either electro-magnetic device to effect an initial drive of the associated support. 90

10. In a twin phonograph, the combination of a pair of record supports; a motor; an electrical system for driving said supports in alternation from the motor and including a circuit for the motor; means for closing and opening the motor circuit to start and stop the drive; a controller board to which the terminals of the motor circuit are connected; and means carried by said board for effecting an initial selective drive of either support. 100

11. In a twin phonograph, the combination of a pair of record supports; a motor; an electrical system for driving said supports in alternation from the motor and including a circuit for the motor and a pair of electro-magnetic devices for determining the support to be driven; means for closing and opening the motor circuit to start and stop the motor; and means for selectively energizing either electro-magnetic device to effect an initial drive of the associated support. 115

In testimony whereof I have affixed my signature.

INDALECIO NORIEGA.
